Primary Examiner — John M Otte

(57) **CLAIM**

The ornamental design for a display screen or portion thereof with a graphical user interface, as shown and described.

DESCRIPTION

The FIGURE is a front view of a display screen or a portion thereof with a graphical user interface.

1 Claim, 1 Drawing Sheet

The screenshot displays the Digital Twin Creator interface, which is a cloud-based platform for creating and managing digital twins. The main workspace is divided into several sections, each containing a list of components with their corresponding 3D models and detailed descriptions. The sections include: 1. **HEATING**: Contains components like Radiator, One Way Valve, Two Way Valve, Three Way Valve, Circulator Pump, and Heat Exchanger. 2. **COOLING**: Contains components like Chiller, Heat Pump, and Heat Exchanger. 3. **WATER**: Contains components like Pump, Heat Exchanger, and Variable Speed Pump. 4. **REFRIGERATION**: Contains components like Compressor, Condenser, and Expansion Valve. 5. **VALVES**: Contains components like Check Valve, Globe Valve, and Ball Valve. 6. **PIPEWORK**: Contains components like Pipe, Tee, and Elbow. 7. **STRUCTURE**: Contains components like Foundation, Wall, and Column. 8. **HAZARDOUS**: Contains components like Flame Arrestor and Safety Valve. 9. **ACCESSORIES**: Contains components like Filter, Strainer, and Valve. 10. **LIBRARIES**: Contains sections for Hydraulics, Cooling Sources, Heat Exchangers, Heat Pumps, and Heat Storage. The interface includes a top navigation bar with icons for Home, Create, Share, and Help, and a bottom navigation bar with icons for Home, Create, Share, and Help.
